PRIMING DEVICE

John B. Dyer, Pendleton, Ind., assignor, by mesne assignments, to General Motors Corporation, Detroit, Mich., a corporation of Delaware

Application May 23, 1930, Serial No. 454,915

13 Claims. (Cl. 123—179)

This invention relates to a priming device for internal combustion engines, and particularly to priming devices which are controlled by the starter switch and operated simultaneously with the starting motor.

It is the object of the present invention to provide means for forming a mixture of air and finely divided liquid fuel and fuel vapor and for delivering this mixture to the intake ports of the engine under pressure on operation of the starting motor, so that a highly combustible fuel charge is delivered to the engine cylinders during operation of the starting motor.

It is a further object of this invention to provide means for controlling the admission of fuel and air to the atomizing device automatically, so that fuel and air are supplied by the atomizing device only during such time as the starting motor is operated.

These objects are accomplished according to the present invention by the provision of an atomizing device to which fuel is fed from the ordinary vacuum tank, and in which the fuel is broken up and mixed with air by a power driven rotor which forces the mixture thus formed under pressure, through conduits communicating with the intake manifold of the engine at a point immediately adjacent the engine intake ports. The atomizer is driven by a separate motor and is arranged in circuit with the starting motor so that such motor is set into operation whenever the starting switch is operated, while automatically operated valves are provided which are opened to admit fuel and air to the atomizing device only when the rotor in said device is in operation.

Further objects and advantages of the present invention will be apparent from the following description, reference being had to the accompanying drawing wherein a preferred embodiment of one form of the present invention is clearly shown.

In the drawing:

Fig. 1 is a side elevation of an engine provided with the present invention.

Fig. 2 is an enlarged view of the atomizer device with parts broken away to show other parts in section.

Fig. 3 is a detail view showing the parts in inoperative position.

Fig. 4 is a detail section on line 4—4 of Fig. 2.

Referring to Fig. 1 of the drawing, the reference numeral 10 indicates the cylinder block of a six cylinder engine of conventional type. The reference numeral 12 indicates the intake manifold,

to which a carburetor 14 of conventional form supplies a combustible mixture in the usual way. The fuel reservoir 16 of the carburetor is adapted to be supplied with fuel from the ordinary vacuum tank 18 of well-known construction, this vacuum tank being also effective to supply fuel to the atomizing device which constitutes the present invention, and which is hereinafter described in detail. The starting motor is indicated at 20 and is controlled by a switch 22 mounted on 10 the floor board 24 of the vehicle in the usual way.

It is ordinarily difficult to start internal combustion engines when equipped with carburetors of the conventional type for the reason that fuel is not distributed properly to the various cylinders, there being a very slight velocity of flow through the manifold at such time due to the low speed at which the starting motor turns the engine and the air restriction effected by the choke and throttle. The fuel which is supplied to the manifold from the carburetor, although delivered to an area in which a high suction is maintained, will follow irregular paths through the manifold, some of it being precipitated on the walls thereof, and will be delivered in variable quantities 15 to the various different cylinders. According to the present invention, the fuel which is employed for starting purposes is not delivered to the inlet end of the intake manifold, but is admitted to the manifold close to the outlet ends of the various 20 delivery branches and is delivered thereto under pressure in the form of a mixture of very finely divided fuel particles suspended in air moving at high velocity, so that substantially the same 25 quantity of fuel will be delivered to the various 30 cylinders in a form which is readily ignited.

In order to accomplish the result above referred to, applicant has provided an atomizing device indicated in its entirety by the reference numeral 26, which is secured by bolts 28 to a support projecting from the engine block. The atomizing device comprises a rotating element 30 mounted on the armature shaft 32 of an electric motor 34, so as to be rotatable therewith or movable axially thereto, in a manner fully described hereinafter.

The rotating element 30 is located within a housing 36 secured in any desirable manner to the motor housing and comprises a blower fan having a hub 38, a projecting flange 40 integral 50 therewith and spiral fan blades 42. Within the hub 38, spaced therefrom and integral therewith, is a sleeve 44, the interior of which is threaded to engage a steep pitch thread 46 formed on the motor shaft. In the space between the sleeve 44

and hub 38 is received a helical spring 40, the function of which is described later. One end of the spring engages the solid end of the hub while the other presses against a collar 50 secured to the motor shaft.

The end of the hub member 38 is beveled as indicated at 52 to form a valve surface which cooperates with a seat 54 on the housing to regulate the admission of air and fuel to said housing. Air and fuel are supplied to the housing through a nipple 56 integral therewith and projecting therefrom, said nipple having air ports 58 therein controlled by a ring valve 60. The end of the nipple is threaded and connected thereto by a reducing coupling 62 screwed on the nipple is a fuel pipe 64 which supplies fuel through a restricted fuel inlet 66, controlled by a conical valve 68 screwed on the end of a pin 70 which is slidable in a reduced extension 72, projecting 20 from the hub 38. This valve is normally held in the position shown in Fig. 3, by a helical spring 74 received between the valve end and the end of the hub, but the valve may make a limited movement with respect to the hub, the amount of this movement being determined by the distance between the valve and the extension 72.

The fuel pipe 64, is connected by means of a T-coupling with the carburetor fuel supply line between the vacuum tank 18 and the float bowl 16 of the carburetor, the flow of fuel therethrough being controlled by the valve 68 in the manner hereinafter described.

The housing 36 is provided with an outlet connection 76 in which a delivery pipe 78 is connected in any desirable manner. The pipe 78 is connected by a T-coupling to a pipe 80 which extends longitudinally of the engine and is provided with branches 82, 84 and 86 leading to the three outlet branches of the intake manifold at a point closely adjacent the connection of such branches with the engine block.

A binding post 88 is connected by a wire 90 with the binding post 92 on the starting motor which is connected with the starting switch 94 hereinbefore referred to. It will be obvious that whenever the starting switch is operated, the motor 34 will be operated as well as the starting motor 26.

The operation of the device is as follows: The parts are in the position shown in Fig. 3 before the engine is started or when it is running normally, and in such position of the parts the valves 52 and 68 are held closed by springs 48 and 74, preventing admission of either fuel or air to the housing 36. Since the valve 68 has a limited movement with respect to the valve 52, inaccuracies of manufacture are compensated for and accurate closing of both valves is secured. On operation of the starting switch the motor 34 is started and the action of the screw thread 46 is effective to move the rotating element 30 to the right, to the position shown in Fig. 2, to admit fuel and air to the housing 36. After the rotor has been moved to this position it is rotated with the shaft of the motor 34 to thoroughly mix the air and fuel within the housing and to deliver the mixture thus formed through the delivery conduits above described to the outlet branches of the manifold. As soon as the starting switch is permitted to return to normal position the operation of the motor 34 ceases and the springs are effective to close the valves 52 and 68 as the rotor 30 is moved to the left to its initial position.

As the mixture formed in the atomizing device 75 is a substantially homogeneous one and is

forced through the delivery conduits under pressure, the velocity of flow is relatively high and fuel distribution substantially uniform. Also as the mixture is delivered at a point close to the intake ports there is little or no opportunity for the fuel to precipitate out of the mixture before it reaches the cylinders.

While the form of embodiment of the present invention as herein disclosed, constitutes a preferred form, it is to be understood that other forms might be adopted, all coming within the scope of the claims which follow.

What is claimed is as follows:

1. A priming device for an internal combustion engine comprising conduits adapted to deliver fuel to the intake ports, and means including an atomizing device for forming a mixture of fuel and air and for delivering said mixture under pressure to the intake ports of the engine, said atomizing device comprising a rotor, a housing therefor, means for admitting air and fuel to the housing, and a plurality of valves on the intake side of said housing, said valves being operated by said rotor for controlling the admission of fuel and air to said housing. 15

2. A priming device for an internal combustion engine comprising conduits adapted to deliver fuel to the intake ports, an atomizing device for forming a mixture of fuel and air, and means for delivering said mixture under pressure to the intake ports of the engine, said atomizing device comprising a rotor, a housing therefor, means for admitting air and fuel to the housing, normally closed valves for controlling the admission of fuel and air to said housing and means whereby said valves are operated through the medium of the rotor. 30

3. A priming device for an internal combustion engine comprising conduits adapted to deliver fuel to the intake ports, an atomizing device for forming a mixture of fuel and air, and means for delivering said mixture under pressure to the intake ports of the engine, said atomizing device comprising a normally stationary rotor, a housing therefor, means for admitting fuel and air to said housing, a plurality of normally closed valves on the intake side of said housing for controlling the admission of air and fuel, and means for opening said valves when the rotor is started. 40

4. A priming device for an internal combustion engine comprising in combination, a manifold adapted to supply fuel mixture to the intake ports, conduits adapted to deliver fuel to the manifold adjacent said intake ports, an atomizing device for forming a mixture of fuel and air, and for delivering said mixture under pressure to said conduits, said atomizing device comprising a normally stationary rotor, a housing therefor, means for admitting fuel and air to said housing, 55 valves for controlling the admission of air and fuel, a power operated shaft for driving said rotor having helical threads thereon engaging said rotor whereby the rotor is movable axially of said shaft and rotated thereby, and means 60 whereby the axial movement of the rotor is effective to open said valves. 65

5. A priming device for an internal combustion engine comprising conduits adapted to deliver fuel to the intake ports, and means including an atomizing device for forming a mixture of fuel and air and for delivering said mixture under pressure to said conduits, said atomizing device comprising a rotor, means for axially and rotationally moving said rotor, a housing there- 70

for, means for admitting fuel and air to said housing, valves for controlling the admission of fuel and air, and means for operating the valves during axial movement of the rotor.

- 5 6. A priming device for an internal combustion engine comprising conduits adapted to deliver fuel to the intake ports, an atomizing device for forming a mixture of fuel and air, and means for delivering said mixture under pressure to the 10 intake ports of the engine, said atomizing device comprising a rotor, a housing therefor, means for admitting air and fuel to the housing, and valves on the rotor for controlling the admission of fuel and air to said housing.
- 10 7. A priming device for an internal combustion engine comprising conduits adapted to deliver fuel to the intake ports, an atomizing device for forming a mixture of fuel and air, and means for delivering said mixture under pressure to the 15 intake ports of the engine, said atomizing device comprising a rotor having axial and rotational movement, a housing therefor, means for admitting fuel and air to said housing, valves on the rotor for controlling the admission of fuel and 20 air to said housing, and means for moving the rotor axially to open said valves.
- 15 8. A priming device for an internal combustion engine comprising conduits adapted to deliver fuel to the intake ports, an atomizing device for forming a mixture of fuel and air, and means for delivering said mixture under pressure to the 25 intake ports of the engine, said atomizing device comprising a rotor having axial and rotational movement, a housing therefor, means for admitting fuel and air to said housing, valves on the rotor for controlling the admission of fuel and air to said housing, a starting motor, and means for moving said rotor axially on operation of the starting motor to open said valves.
- 30 9. A priming device for an internal combustion engine comprising in combination, a manifold adapted to supply fuel mixture to the intake ports, conduits adapted to deliver fuel to the manifold adjacent said intake ports, an atomizing device for forming a mixture of fuel and air, and for delivering said mixture under pressure to 35 said conduits, said atomizing device comprising a normally stationary rotor, a housing therefor, means for admitting fuel and air to said housing, normally closed valves for controlling the admission of air and fuel, a starting motor, and means operated by said rotor for opening the valves when the rotor is operated by the starting motor.
- 40 10. A priming device for an internal combustion engine comprising conduits adapted to deliver fuel to the engine intake ports, an atomiz- 45
- 45
- 50
- 55
- 5
- ing device for forming a mixture of fuel and air and for delivering said mixture to said conduits, said atomizing device comprising a rotor, a housing therefor, valve means for controlling the admission of air and fuel to the housing, a starting motor, auxiliary motor for driving said rotor and in circuit with the starting motor, a shaft driven by said auxiliary motor and having helical threads thereon engaging the rotor whereby the rotor is movable axially of said shaft and rotated thereby, and means whereby the axial movement of said rotor operates said valve means.
11. A priming device for an internal combustion engine comprising conduits adapted to deliver fuel to the intake ports, an atomizing device for forming a mixture of fuel and air, and means for delivering said mixture under pressure to the intake ports of the engine, said atomizing device comprising a rotor, a housing therefor, means for admitting air and fuel to the housing, and separate valves operable by the rotor for controlling the admission of fuel and air to said housing, one of said valves being fixed relative to the rotor and the other being movable relative thereto.
12. A priming device for an internal combustion engine comprising conduits adapted to deliver fuel to the intake ports, an atomizing device for forming a mixture of fuel and air, and means for delivering said mixture under pressure to the intake ports of the engine, said atomizing device comprising a rotor, a housing therefor, means for admitting air and fuel to the housing, separate valves carried by the rotor for controlling the admission of fuel and air to said housing, one of said valves being fixed on said rotor and the other being movable thereon, and yielding means for holding said last named valve closed when the rotor is in normal position.
13. A priming device for an internal combustion engine comprising conduits adapted to deliver fuel to the intake ports, an atomizing device for forming a mixture of fuel and air, and means for delivering said mixture under pressure to the intake ports of the engine, said atomizing device comprising a rotor, a housing therefor, means for admitting air and fuel to the housing, separate valves carried by the rotor for controlling the admission of fuel and air to said housing, said valves being coaxial and one of said valves being fixed on said rotor and the other being movable thereon, and yielding means for holding said last named valve closed when the rotor is in normal position.
